ATTORNEY

UNITED STATES PATENT OFFICE.

RALPH E. MATHIS, OF ST. LOUIS, MISSOURI.

WEDGE-LOCK.

1,367,617.

Specification of Letters Patent.

Patented Feb. 8, 1921.

Application filed November 20, 1919. Serial No. 339,466.

To all whom it may concern:

Be it known that I, RALPH E. MATHIS, a citizen of the United States of America, residing at the city of St. Louis, State of Missouri, United States of America, have 5 invented a certain new and useful Wedge-Lock, of which the following is such a full, clear, and exact description as will enable any one skilled in the art to which it appertains to make and use the same, reference being had to the accompanying drawings, forming part of this specification.

10 My invention relates to a wedge lock and particularly to means for locking the wedge and brass of a railway journal bearing together to prevent the theft of the latter from the journal box.

15 In the accompanying drawings which illustrate one form of wedge lock made in accordance with my invention together with a railway journal box to which the same is applied, Figure 1 is a vertical longitudinal section, Fig. 2 is a front view, the journal box and axle being omitted, Fig. 3 is a top 20 plan view of the wedge, and Fig. 4 is an enlarged section taken on the line 4-4 of Fig. 3.

25 5 indicates the railway journal box, 6 the axle, 7 the brass, and 8 the wedge all of 30 which parts may be of the standard M. C. B. type.

35 9 is an upwardly extending apertured projection which may be either formed integral with the brass 7 or secured thereto by means 40 of a stud 10 as shown in the drawings. The projection 9 enters a slot or recess 11 formed in the wedge 8, and engages with a shoulder 15 formed by the junction of the recess 11 with a rearwardly extending tapering passage 24. The projection 9 is adapted to be 45 engaged by a rod 12 threaded at its outer end and situated in a passage 13 formed in the body of the wedge. The threaded portion of the rod 12 engages with a nut 14 50 cast in the wedge 8. The outer end of the rod 12 is provided with a key engaging portion 16 and is situated in an enlargement 17 of the passage 13. The lip 18 of the wedge prevents a straight key from directly 55 engaging with the portion 16 of the locking rod. In order to allow the removal and insertion of the locking rod 12, the parts should be so proportioned that after the threaded portion of the rod 12 is disengaged from the nut 14, its forward part can be tipped downwardly so as to pass the lip 17

of the wedge. 19 is a key which is adapted to operate the rod 14 by engaging with the portion 16 of the rod and provided with a universal joint 20 to allow it to be inserted 60 into the passage 17 at an angle as shown in Fig. 4 of the drawings.

65 In the normal position of the parts the front end of the wedge 8 engages with detents 21 formed on the box 5 and the front end of the brass engages with a collar 22 on the end of the axle 6. In order to remove the wedge and brass, the box 5 is moved upwardly relative to the axle 6, but this movement is limited by the engagement 70 of the lower side of the axle with the end of the axle slot 23. The amount of movement in a standard M. C. B. box is not sufficient to allow the wedge and brass to be removed together and consequently while the 75 parts are locked together by my device it is impossible to remove either. By disengaging the wedge from the brass, however, the wedge may be raised sufficiently to disengage the projection 9 from the shoulder 15 80 and thus allow the withdrawal of the wedge. The passage 24 being of such size as to produce the necessary space between the top of the brass and the box for the passage of the wedge. 85

It will be evident that the wedge cannot be disengaged from the brass without the use of a key which not only fits the projecting portion of the rod, but is also provided with a universal joint to allow its angular 90 engagement with the rod. Inasmuch as the brass cannot be removed from the journal box without first removing the wedge it offers an effective means for preventing 95 the theft of the brass.

Having fully described my invention, what I claim as new and desire to secure by Letters Patent of the United States is:

1. The combination with a railway brass of a wedge provided with longitudinally 100 movable locking means engaging with the brass, and a downwardly projecting lip on said wedge protecting said locking means for direct engagement from the front of the axis.

2. The combination with a railway brass of a wedge provided with longitudinally 110 movable locking means engaging with the brass, a downwardly projecting lip on said wedge protecting said locking means from direct engagement from the front of the axle box, and a key provided with a uni-

versal joint for engaging and actuating said locking means.

3. The combination with a railway brass provided with an upwardly extending apertured projection, of a wedge, and a longitudinally movable threaded rod carried by the wedge and adapted to engage with said projection to lock the said parts together.

4. The combination with a railway brass,

provided with an upwardly extending apertured projection, of a wedge provided with a longitudinal passage, a slot to receive said projection, a threaded rod in said passage and adapted to engage with said projection, and a threaded nut engaging with said rod.

In testimony whereof, I have hereunto set my hand and affixed my seal.

RALPH E. MATHIS. [L.S.]
